UNITED STATES PATENT OFFICE.

LOUIS J. HIRT, OF BROOKLINE, MASSACHUSETTS.

COLLECTOR FOR ELECTRIC RAILWAYS.

SPECIFICATION forming part of Letters Patent No. 583,575, dated June 1, 1897.

Application filed September 6, 1895. Serial No. 561,602. (No model.)

To all whom it may concern:

Be it known that I, LOUIS J. HIRT, a citizen of the United States, and a resident of Brookline, in the county of Norfolk and State 5 of Massachusetts, have invented certain new and useful Improvements in Collectors for Electric Railways, of which the following is a specification.

My invention relates to those electric rail- 10 ways in which the electric conductor which conveys the electricity is contained in a conduit below the level of the street; and it consists of a novel construction of the contact- plow or collector by which the current is con- 15veyed from the conductor to the motor.

In the accompanying drawings, illustrating my improvement, Figure 1 is a side elevation of the plow. Fig. 2 is an end elevation of the plow in position in the conduit. Fig. 3 is 20 a plan view, and Fig. 4 is a modification.

My improvement consists, essentially, in a plow having a series of contact-points on the supply-conductors, and, furthermore, in a plow provided with appliances for cleaning 25 and brightening the conductor, whereby a more effectual contact is made and the passage of the electric fluid from the conductor to the motor on the car is facilitated.

The drawings show the preferable form of 30 my improvement. As there seen the upper part of the plow consists of a metal frame formed of the side strips *a a*, connected to which are thin metal plates *a' a'*, fastened together so as to leave spaces for conducting- strips *b b*, which extend through the plow. On both sides of the lower portion of the metal frame are secured wooden panels *c c*, which completely inclose the lower end of the frame and project some distance below it. 35 Between the lower end of the wooden panels and projecting some distance beyond it is secured an insulating-plate *d*, formed of any suitable insulating material. The wooden panels are shown bolted to the metal plate *a a'* 40 and to the insulating-plate *d*, but they may be fastened in any suitable manner. To the bottom of the wooden panels on each side of the plow are secured a series of spring-plates *e*, formed to flare outward and provided on 45 three ends with contact-shoes *f*. The bottom of the insulating-plate *d* should project be-

low the line of the contact-shoes or lower ends of the plates *e*, so as to completely insulate the plates on the opposite ends of the plow from each other. In the construction shown 55 in the drawings there are three of these contact-plates *e* on each side of the plow, as I have found that number gives the best results, but the number may be varied if found desirable. Leading from the contact-shoes *f* 60 are conducting-wires *h h*, which extend back to the insulating-plate and connect with the conducting-strips *b*, which project from the wooden panels on the side of the plate *d*.

The plow thus constructed is suspended in 65 the conduit from the car in the usual manner, so that the contact-shoes on the ends of the spring-plates *e* rest and bear against the electric conductors *l* in the conduit, and the connection is made with the motor in any 70 suitable manner. By means of the insulating-plate *d* between the series of contact-plates *e* on each side of the plow the electricity gathered by the contact-plates on one side cannot pass to the other side without 75 passing through the plow, and thus through the motor, and the wooden panels effectually insulate the contact-plates from the metal frame *a a'* and prevent the escape and loss of 80 the electric fluid.

It frequently occurs that, owing to dampness or some such cause, the plow will slide along the electrical conductor in the conduit and not make a complete contact with the latter. With my improved construction, by 85 reason of the three contact-points on the conductor, the contact of the plow is certain to be sure and complete, as if the first shoe *f* does not make a sufficient contact the other shoes following immediately after it are cer- 90 tain to do so, and any dampness which may be on the wire will be removed by the first shoe or contact-point, leaving the electrical conductor clean for the other and following shoes. 95

In Fig. 4 is shown a modified construction in which one of the shoes *f* is replaced by a brush for cleaning the electrical conductor. This brush, as it is on the plow itself, while it is designed merely to remove any dampness 100 or dirt from the conductor, in no wise affects the flow of the electricity or causes any loss of

the latter, as any electric fluid taken off by the brush or cleaner merely flows through the plow in the usual manner.

What I claim is—

- 5 1. In an electric collector for railroads, in combination, the frames *a* and *d*, wooden panels *c*, conducting-strips *b* whereby the current is conveyed from the contact-plates through the plow, and a series of contact-plates *e* on each side of the plow, substantially as described.
- 10 2. In an electric collector for railroads, in

combination, a frame suspended from the car, a series of contact-plates *e* on each side of the frame and insulated therefrom, conducting-strips whereby the current is conveyed from the contact-plates through the collector, and the insulator *d* between the series of contact-plates on each side of the frame, substantially as described. 15
